UNITED STATES PATENT OFFICE.

WILLIAM P. BECKER, OF PELHAM, NEW YORK, ASSIGNOR TO THE NEW YORK LAST COMPANY, OF NEW YORK, N. Y., A CORPORATION OF NEW YORK.

LAST.

Application filed February 19, 1926. Serial No. 89,288.

My invention relates to improving the heel structure of wooden lasts of either the divided type or that type having a removable instep portion.

5 In lasts of the type to which my invention relates the heel is provided with a thimble hole for jacking the last, and between this thimble hole and the rear face of the last with a bore for receiving a nail, 10 screw or other fastening means for attaching wooden heels to shoes being manufactured upon the last.

The last in manufacturing shoes is necessarily subjected to very rough usage and in 15 certain stages of the manufacture of shoes it is necessary to drive the last into the shoe. The driving or hammering is done on the rear face of the last, and inasmuch as the last has been weakened by the thimble hole 20 and bore, above referred to, the last is soon cracked or crushed so as to be useless.

It is an object of my invention, therefore, to so construct the last heel that this cracking and crushing of the heel are overcome 25 or at least reduced to a minimum. To this end, therefore, I interpose means between the thimble hole and the rear face of the last heel which will enable the last to successfully withstand hammering and rough 30 usage without being crushed or cracked.

More specifically, I provide a fibre or other resilient pad on the upper face of the heel structure, my improved means co-operating with this pad in such a way that the 35 shock of the hammer blows is taken up by my improved structure and the pad, instead of being absorbed entirely by the wood of the last. Inasmuch as the heel bore is intermediate the thimble hole and the rear face 40 of the last, I insert my reinforcing member in the heel bore, thereby not only accomplishing my purpose but providing at the same time a guide for the drill or other tool which is passed down through this bore into 45 the heel of the shoe, and means for preventing injury to this bore.

In the preferred embodiment of my invention I employ a metal ferrule which I insert in the heel bore, this ferrule being provided 50 with an enlarged head embedded in the fibre pad, above referred to, so that the shock of a hammer blow will be absorbed by the ferrule and paid. Inasmuch as the wood of the last expands and contracts more or less un-

der atmospheric changes, I only project the 55 ferrule part way through the heel bore, having the upper part only of the heel bore enlarged for this purpose so as to provide a shoulder or abutment about midway of the heel bore against which the ferrule is driven. 60 This effectually prevents further movement of the ferrule into the bore, and also prevents the lower end of the ferrule from projecting beyond the lower end of the heel bore when the last shrinks, to eliminate all danger 65 of the ferrule injuring the shoe. Movement of the ferrule in an upward or outward position with respect to the heel bore is prevented by providing the ferrule with spurs, which cut into the wood of the last 70 and hence prevent its upward or outward movement.

In the accompanying drawing I have 75 illustrated an embodiment of my invention—

Figure 1 showing the heel part of my improved last partly in section, with my improvement incorporated therein; and

Fig. 2 is an enlarged view of the ferrule which I employ.

Referring to the drawings in detail, 1 designates a wooden last, and 2 the heel thereof. The upper face of the heel structure is provided with a pad 3 of fibre, leather, or some similar resilient material. 85 The fore part of this resilient pad and the heel 2 are provided with a thimble hole 4 and thimble 5. This thimble hole passes about half way only through the last, and is provided for receiving a last jack in the 90 operation of jacking the last.

Intermediate the thimble hole 4 and the rear face 6 of the last, and in line with the thimble hole 4, I provide a heel bore 7, this bore passing down through the pad 3 and 95 the wood of the last heel, from the upper face 8 of the last heel to and through the lower face 9 of the last heel.

To prevent cracking and crushing of the last from hammer blows on the rear face 100 6 thereof, the upper part 10 of the bore 7 is enlarged to provide a shoulder 11 approximately midway of the bore, and in this enlarged upper part of the bore I insert a metal ferrule 12, having an enlarged head 105 13 which is sunk into the resilient pad 3, and with spurs 14 along its body extending outwardly and upwardly with respect to the

long axis of the ferrule. These spurs effectually prevent the ferrule from working out of the bore.

It will be seen from the foregoing that 5 I have provided a last structure in which cracking or crushing of the last due to the last having been weakened by the heel bore is effectually prevented by the provision of the metal ferrule 12, the shock of the 10 hammer blows on the last heel being absorbed by the ferrule and the resilient pad 3.

It will be seen also that my improved last has been so constructed that the shoe cannot be injured by the ferrule, the latter 15 with this in mind having been purposely made shorter than the depth of the heel of the last, thereby permitting the wood of the last to expand and contract without danger of the end of the ferrule projecting beyond 20 the lower face of the last.

This application is a continuation in part of my application Serial No. 703,356, filed April 1, 1924.

What I claim is:

A last comprising a wooden heel structure, said heel being provided with a bore extending vertically thereof from the upper face thereof to and through the lower or bottom face, an internal shoulder in said bore intermediate the ends thereof, a resilient pad 25 on the upper face of said last, and a headed metal ferrule lying in said bore and provided with integral means for preventing withdrawal, the lower end of the ferrule 30 terminating short of the bottom face of the last and abutting said shoulder, the head resting upon and being set into said pad.

This specification signed this 15th day of February, 1926.

WILLIAM P. BECKER.
